UNITED STATES PATENT OFFICE.

ALBERT E. SEHLBACH, OF CHICAGO, ILLINOIS, ASSIGNOR TO ALBERT PICK & COMPANY, OF CHICAGO, ILLINOIS, A CORPORATION OF ILLINOIS.

DESIGN FOR A GOBLET.

Application filed September 6, 1927. Serial No. 23,296. Term of patent 14 years.

To all whom it may concern:

Be it known that I, ALBERT E. SEHLBACH, a citizen of the United States, residing at Chicago, in the county of Cook and State of Illinois, have invented a new, original, and ornamental Design for a Goblet, of which the following is a specification, reference being had to the accompanying drawing, forming a part thereof.

In the drawing: Fig. 1 is a perspective of a goblet embodying my new design. Fig. 2 is a side elevation shown on a reduced scale.

I claim:

The ornamental design for a goblet, as shown.

Chicago, Illinois, May 27th, 1927.

ALBERT E. SEHLBACH.
